DUPPLICATOR

Filed May 17, 1930

UNITED STATES PATENT OFFICE

JAMES DURKIN, OF PITTSBURGH, PENNSYLVANIA

DUPLICATOR

Application filed May 17, 1930. Serial No. 453,159.

This invention relates to duplicating devices and more in particular to duplicators having a stationary gelatinous printing surface.

The primary object of this invention is to provide a duplicator having two stationary gelatinous working surfaces instead of but one such surface, as is now the case with duplicators of this type on the market.

Another object is to provide in a duplicator simple means for renewing or exchanging the stationary gelatinous working surfaces with speed and ease.

A further object of this invention is to provide a duplicator having a canvas-backed stationary gelatinous working surface which may be adjusted as to position and tension. Yet another object of this invention is the provision of a duplicator which is simple in construction and operation and which may be manufactured at relatively low cost.

Additional features and advantages of this invention will appear in the following description considered in connection with the accompanying drawing forming a part of this application, and in which:

Fig. 1 is a front elevation of my duplicator.

Fig. 2 is a sectional view taken substantially on line 2—2 in Fig. 1.

Fig. 3 is a perspective view of the device.

Figs. 4 and 5 are sectional, fragmentary, views showing the manner of rotatably supporting the winding roller of the duplicator on the frame thereof.

Fig. 6 is a side elevation of the clamping bar of the device.

Fig. 7 is an end view of Fig. 6.

Referring to the drawing, a duplicator built according to my invention comprises a main frame consisting of a flat base 1, made of wood or any other suitable and desired material, having straight longitudinal sides and a half-round lower transverse side 2. The corners of the upper, straight, transverse side 3 are rounded off, as at 4, to prevent injury to the stationary gelatinous working surface, commonly called the film, 5 which is stretched taut on both flat surfaces of the base 1.

Guide rails or runners 6 are secured in any desired manner on both longitudinal sides of the base. These runners are wider than the thickness of the base and extend at both sides thereof to provide clearance space for the gelatinous film and protect the latter against contact and friction with the top of the table or desk upon which the device is placed. These runners serve also as guides for the sheets upon which printing is to be duplicated. To prevent marring the surface of the table, etc., upon which the duplicator is used, it is preferable to cover the top and bottom sides of the runners with a lining 7 of felt, or any other suitable and desired material, which lining also keeps the duplicator from sliding too freely on said table, etc.

The canvas-backed duplicating film 5 is removably and adjustably secured on the device by means of the clamping-bar 8 and the winding-roller 9.

As shown in Figs. 6 and 7 in particular, the clamping-bar comprises a substantially cylindrical bar 10 having a flat portion 11 and a corrugated portion 12. At one end of the bar there is secured on the flat portion thereof the handle 13 by means of which the clamping-bar may be rotated.

The winding roller consists of the cylindrical body portion 14, made of wood or any other suitable and desired material, having a diametral and longitudinal slot 15 into which one end of the duplicating film 5 is inserted. One end of the body portion is secured by means of a pin 16 in a ferrule 17 having a centrally disposed trunnion 18. The other end of said body portion is also fastened by a pin connection 19 to another ferrule 20, to which are secured the ratchet-wheel 21 and the turning shaft 22, the latter provided with a turning handle 23.

The clamping-bar and the winding roller are rotatably mounted in suitably apertured brackets 24, 25 fastened by means of screws 26, or otherwise, to the outer lateral sides of the runners 6.

Upon the bracket 25 is rockably mounted a pawl 27 provided with a holding-lug 28 and normally held in engagement with the

100

ratchet-wheel by a spring 29. The clamping-bar 8 is held in place against longitudinal movement by its handle 13 and by a pin 30 driven through the bar 10, at the opposite end.

5 The preferred procedure for mounting the duplicating film on the device is substantially as follows: The clamping-bar is turned around so that its flat portion 11 faces the top end 3 of the base 1, thereby providing space for the insertion of the film therebetween. The clamping-bar is then rotated to bring its corrugation in engagement with the gelatinous side of the duplicating film, whereby the latter is securely clamped. The 10 film is now loosely wrapped about both flat faces of the base 1 and the free end of the film is then inserted in the slot 15 of the winding-roller. By rotating the latter in the proper direction, the film may be stretched taut on the base, and it will be held in this 15 condition by the agency of the ratchet and pawl mechanism fully described above.

20 To remove the duplicating film, the winding-roller is rotated backwards by first pressing on the lug 28 of the pawl 27 to disengage the latter from its ratchet-wheel. This 25 releases the tension in the film and, by rotating the clamping-bar out of engagement with the film, the latter may be quickly removed.

30 While I have illustrated herein the present construction of a novel duplicating device having two stationary gelatinous working surfaces, instead of only one as heretofore 35 available in the trade, it may be found desirable after continued experience to make slight changes in the construction and arrangement of the details of this invention, and I intend to include all such variations in this application, as fall within the scope of the appended 40 claims.

I claim:

45 1. In a duplicator, a base; a flexible stationary gelatinous duplicating film; means to removably secure said film to expose its effective surface on two sides of said base.

50 2. In a duplicator, a base; a flexible stationary gelatinous duplicating film; and means to removably secure said film to expose its effective surface on two sides of said base.

55 3. In a duplicator, a base; a flexible stationary gelatinous duplicating film; means to removably secure said film to expose its effective surface on two sides of said base, and means to stretch said film on said base.

60 4. In a duplicator, a base; a flexible stationary gelatinous duplicating film; means to removably secure said film to expose its effective surface on two sides of said base, and adjustable means to stretch said film about said base.

65 5. In a duplicator, a base; a flexible stationary gelatinous duplicating film; means to removably secure said film to expose its effective surface on two sides of said base; adjust-

able means to stretch said film about said base, and means to hold the film in stretched condition.

6. In a duplicator, a base; a flexible stationary gelatinous duplicating film; means to removably secure said film to expose its effective surface on two sides of said base; means to stretch said film on the base, and spacer means adapted to hold said film in spaced relation to the surface on which said duplicator is positioned.

70 75 In testimony whereof I affix my signature.
JAMES DURKIN.
